WILLIS A. INGALLS, OF SYRACUSE, NEW YORK

KNITTING MACHINE

Application filed March 26, 1928. Serial No. 264,582.

This invention relates to a knitting machine of any type in which two or more sets of knitting needles such as the cylinder set and plate or dial set having the usual hook and latch are employed, and refers more particularly to a means for automatically transferring the yarn from the needles of one set to the needles of the other set as, for example, in changing from a rib stitch fabric to a plain stitch fabric.

The main object is to incorporate in a machine of this character, simple and efficient means whereby the knitting of the fabric may be automatically changed from one stitch to the other.

One of the specific objects is to associate with the knitting needles of one set, separate relatively movable transfer members which may be progressively actuated by a suitable cam for sequentially displacing the yarn loops formed by the adjacent needles therefrom and placing them in position to be engaged by needles of the other set.

Other objects and uses relating to the form and relation of the needles and transfer members will be brought out in the following description, taken in connection with the accompanying drawings in which:

Figures 1, 2, 3, 4, 5 and 6 are perspective views of portions of one of the needles of each set, together with portions of one of the transfer members showing different positions of said needles and members in effecting the transfer of the yarn from the needles of one set to the needles of the other set.

Figure 7 is a face view of one of the transfer members.

Figure 8 is a face view of a knitting needle adapted to be associated with the transfer member illustrated in Figure 7.

Figure 9 is a transverse sectional view taken substantially in the plane of the line 9—9, Figure 3, but associated with a suitable guide ring or cylinder.

Figure 10 is a face view of a portion of the fabric stretched out to show the change from one stitch to the other.

Figures 11 and 12 are enlarged sectional views of the fabric taken respectively in the

plane of the line 17—17 and 18—18, Figure 10.

The machine for which my novel transfer mechanism is adapted, may be of the conventional circular type consisting of a set of horizontal or plate knitting needles 1 arranged in circumferentially spaced relation around and upon a circular plate or guide ring not shown, of usual construction and adapted to be reciprocated radially by means of suitable cam rings, also not shown, of the usual construction, for circular knitting machines. Another set of vertically disposed needles 4 is mounted for vertically reciprocatory motion in a suitable guide ring or cylinder 5 to be actuated progressively by a rotary cam member not shown, said cylinder needles being arranged in uniformly spaced relation circumferentially around and upon the inside of the cylinder and in normally staggered relation to the plate needles for knitting a ribbed fabric.

Each cylinder needle 4 has associated therewith a pair of transfer members 7 arranged along opposite sides thereof in the same groove to permit relative vertical movement of the knitting needles and transfer members. The knitting needles 4 are provided near their upper ends with lengthwise grooves 8 in opposite faces thereof for receiving inturned prongs 9 on the extreme upper ends of the transfer members 7 for guiding the knitting needles 4 and transfer members 7 in their vertical movement one upon the other and also for holding them against radial displacement.

The knitting needles 4 are provided with the usual shoulders 11 adapted to ride in cam grooves, not shown, adapted to reciprocate said needles. The transfer members 7 are also provided near their lower ends with offset shoulders 12 adapted to ride in a suitable cam groove not shown, in the periphery of a rotary cam member or wheel. Likewise, it is to be understood that the plate needles 1 are provided with shoulders, similar to the shoulders 11 for the cylinder needles, not shown, adapted to ride in a cam groove and which, together with the cam grooves for the cylinder needles 4 and transfer members 7 may be

constructed in any suitable manner for progressively operating their respective needles 1 and 4.

When knitting ribbed fabric or double plain fabric, I preferably use one-half as many cylinder needles as plate needles and allow alternate plate needles to idle without knitting while the remaining plate needles cooperate with the cylinder needles to form the 10 ribbed fabric in which case, when knitting a plain fabric, the cam groove for the plate needles 1 will be adapted to progressively reciprocate all of the plate needles, but when knitting the ribbed fabric, only alternate 15 plate needles are used in conjunction with the cylinder needles 4 during which time the transfer members 7 will remain in their lowermost inoperative position until such time it is desired to change from the ribbed 20 stitch to a plain stitch, whereupon said transfer members 7 will be caused by their cam groove to move vertically relative to the respective cylinder needles 4 to bring the yarn carried by said needles into position to be 25 received by the corresponding plate needles 1, as will be hereinafter more fully described.

Another object in providing the transfer members 7 with the pointed prongs 9 riding in the grooves 8 is to enable said prongs to enter the yarn loop formed by the needles 4 during the operation of transferring the yarn from the needles 4 to the needles 1. For this latter purpose, the transfer members 7 are provided near their upper ends with shoulders 30 14 projecting laterally beyond the latch side of the needles 4 so that when the yarn loop is formed by the needle and the latter is raised sufficiently to open the latch full open, the shoulders 14 will then be some distance below the end of the open latch, see Figure 2, and as the needle assumes its normal down position and the transfer member is raised, said shoulders will engage opposite sides of the loop to force the same upwardly thereby 40 closing the latch and permitting the loop to be displaced from the needle 4 into position to be engaged by the adjacent plate needle 1, as shown more clearly in Figure 4, at which time the cylinder needles 4 will have been 45 shifted to register with the adjacent previously idling needles 1 by any suitable mechanism, not necessary herein to illustrate or describe, as it does not constitute any part of this invention.

It is, of course, obvious that when the transfer members 7 are applied to opposite faces of the needle 4, the transfer members will be held in sufficiently spaced relation to permit the entrance of the adjacent needle 1 between 50 their upper ends, as shown in Figure 5, and in order to facilitate the entrance of the needle 1 between the transfer members, the outer edges of the latter are beveled at 15 from the upper edge of the shoulders 14 downwardly 55 a sufficient distance to permit the needles 1

to enter between the transfer members during the transfer operation.

Operation

When knitting with both sets of needles, 70 those of each set will be arranged in staggered relation to those of the other set, while the cams for each set will be arranged and timed to operate both sets of needles in the usual way for ribbed fabric as long as may be 75 required.

When it is desired to change the fabric from a ribbed stitch to a plain stitch, it is necessary to shift a portion or all of one set of needles as 4 circumferentially a sufficient 80 distance to register them with corresponding needles of the other set as 1 and as illustrated in Figure 1 of the drawings. This circumferential shifting movement of the cylinder needles 4 and the transfer members 7 may be 85 accomplished in any suitable manner, not herein necessary to illustrate or describe, and after this shifting movement of the needles 4 is effected to bring the cylinder needles into alignment with the corresponding idle plate 90 needles 1. The cylinder needles 4 may be progressively moved upwardly to bring the loop as —a— below the needle latch, as illustrated in Figure 2, after which the needles 4 are returned to their lowermost position 95 which will cause the loops —a— to close the latch of the needle in the conventional manner and be in position to be removed from the needles 4, as illustrated in Figure 3.

The transfer members 7 for the respective cylinder needles 4 are then progressively moved upwardly during which movement, the prongs 9 of the transfer members will enter the corresponding loops —a— and cause 100 said loops to be engaged by the shoulders 14 of the transfer members and be lifted from the respective needles 4 into a plane above the path of movement of the plate needles 1, as illustrated in Figure 4, after which the corresponding plate needles 1 will be moved 105 forwardly between the respective transfer members 7, as illustrated in Figure 5, after which said transfer members 7 will again be returned to their lowermost position and in so doing, will deposit the loops —a— upon the 110 respective plate needle 1, as illustrated in Figure 6, thereby completing the transfer of the yarn from the cylinder needles to the corresponding plate needles 1 after which the 115 plate needles may be actuated in the conventional manner to knit a plain stitch fabric and the cylinder needles 4, together with the transfer members 7, may be returned circumferentially to their normal positions in a plane intermediate the plate needles 1 and be caused 120 to remain in the lowermost inoperative position so as to permit the free operation of the plate needles for knitting the plain fabric.

What I claim is:

1. In a knitting machine, a needle having 130

the usual hook and latch and provided with lengthwise grooves in its opposite sides extending beyond the latch at the back of the hook, and transfer members slidable along said grooved sides and provided with shoulders projecting laterally beyond the latch and hook edge of the needle for displacing the knit loop formed by said needle therefrom as the transfer member is moved in one direction relatively to the needle, said transfer members having prongs projecting into the adjacent grooves for entering said loop.

2. The combination with a knitting needle having the usual hook and latch for forming a knit loop, said needle having lengthwise grooves in its opposite sides at the back of the hook and latch, transfer bars slidable along the grooved sides of the needle and provided with shoulders projecting beyond the front edge of the needle for displacing the loop from the needle when the bars are moved in one direction, said bars having prongs projecting lengthwise beyond the shoulders and riding in the adjacent grooves for entering the loop and holding it open as it is displaced from the needle.

3. In a knitting machine, a needle having a hook and a latch and provided with lengthwise guides on its opposite sides extending beyond the latch, and transfer members movable along opposite sides of the needle in sliding engagement with said guides for displacing the loop formed by said needles therefrom.

35 4. In a knitting machine, a needle having a hook and a latch and having its opposite sides provided with guide grooves extending lengthwise thereof at the back of the latch and hook, and transfer bars movable along opposite sides of the needle and provided with inturned prongs slidable in said grooves.

In witness whereof I have hereunto set my hand this 22nd day of March, 1928.

WILLIS A. INGALLS.
